UNITED STATES PATENT OFFICE.

ALEXANDER BOGDÁNFFY, OF NEW YORK, N. Y.

CORK-BLOCKING MACHINE.

1,201,247.

Specification of Letters Patent. Patented Oct. 17, 1916.

Application filed February 23, 1915. Serial No. 9,996.

To all whom it may concern:

Be it known that I, ALEXANDER BOGDÁNFFY, a subject of the King of Hungary, and a resident of the city of New York, in the county of Kings and State of New York, have invented certain new and useful Improvements in Cork-Blocking Machines, of which the following is a specification.

The present invention relates to an improved apparatus for cutting or blocking out corks from cork strips.

More particularly it relates to cork blockers of the automatic type. Cork blocking machines of this character are usually provided with a tubular knife or cutter in combination with a work support, the latter having automatic feeding devices for intermittently advancing the cork strips within the reach of the knife. As corks of different diameters are being cut, the knife obviously has to be replaced. On the other hand, the position of the work support in relation to the knife must be adjusted to correspond to the diameter of the knife, that is to say the work support must be lowered or raised. The stroke of the feeding device must also be varied, it being obvious that the stroke must be larger if corks of larger diameters are to be blocked, and smaller if smaller corks are to be cut. The feeding device usually comprises a reciprocating bar provided with fingers, said reciprocating bar being actuated, for instance, by an oscillating arm. In constructing the machine, this arm must have a swing that will permit it to go beyond the largest knife. Owing to this arrangement, the ends of the cork strips will be wasted if small corks are being cut, the feeding fingers carrying them beyond the knife. Another defect of the cork blocking machines heretofore in use consists in that the feeding fingers or other feeding devices contact either with the upper or lower faces of the cork strips as they are being advanced on the work support. These faces are very uneven, and for this reason the feeding of the strips irregular.

It is now one of the objects of the present invention to obviate these defects, that is to say to produce a feeding device which carries the cork strips on the work holder in relation to the cutting edge of the knife irrespective of the diameter of the latter always to a fixed point from said edge, and which acts upon the sides of the cork strips, that is to say upon the smooth faces thereof, thereby

reducing the waste to a possible minimum and resulting in an even feeding of the same.

Another object of the invention is to devise a cork-blocker which is simple in construction, efficient in operation, and the parts of which can be adjusted by a single setting when a knife is replaced by one of another diameter.

A further object of the invention is to provide the blocker with a cutter in combination with bearings which reciprocate with the cutter arbor, thereby preventing the oil or other lubricating material from being ejected from the bearings, a feature common in blockers heretofore in use.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

Figure 1 is a front elevation, partly in section, of a machine constructed in accordance with the present invention; Fig. 2 is a section taken on line 2—2 of Fig. 1; Fig. 3 is a section taken on line 3—3 of Fig. 2 on a larger scale; Fig. 4 is a section taken on line 4—4 of Fig. 2 also on a larger scale; Fig. 5 is a section taken on line 5—5 of Fig. 2 also on a larger scale; Fig. 6 is a vertical section, partly in elevation, taken through a portion of the feeding mechanism on a larger scale; Fig. 7 is a section taken on line 7—7 of Fig. 6; Fig. 8 is a sectional detail of a portion of the device shown in Fig. 7; Fig. 9 is a section taken on line 9—9 of Fig. 8; Fig. 10 is a side elevation of a double eccentric for actuating the feeding device of the machine; Fig. 11 is a vertical section taken therethrough; Fig. 12 is a front elevation of a detail of the feeding mechanism; Fig. 13 is a side elevation thereof; Fig. 14 is a front elevation of another detail of the feeding mechanism; Fig. 15 is a side elevation of the same; Fig. 16 is a horizontal section

taken through one of the feeding racks; Fig. 17 is a section taken on line 17—17 of Fig. 16; Fig. 18 is a diagram showing the relation of the holes in the sides of the work support through which the cutters of the machine reciprocate; Fig. 19 is a diagram, showing in perspective parts of the feeding mechanism; and Fig. 20 is a diagram, showing in perspective other parts of the feeding mechanism and also the presser feet coöoperating therewith; Fig. 21 is a side elevation of the machine, showing in dotted lines parts in their swung back position; Fig. 22 is a side elevation of the apparatus, showing in dotted lines certain parts in their lowered positions; and Fig. 23 is a perspective view of a portion of the feeding mechanism and its support.

In the drawings, the numeral 20 indicates the main frame of the machine. On this frame are formed bearings 21, each provided with a lining sleeve 22, in which is rotatably mounted the main driving shaft 23 of the machine. To this shaft rotation may be imparted in any suitable manner, for instance there may be keyed to the same a pulley 24, over which runs a belt that is geared to any suitable source of power. In the upper portion of the main frame 20 is formed a horizontal slideway 25, in which is reciprocably mounted a bearing block 26, carrying above each other two sets of bearings 27. In these bearings are rotatably journaled two parallel horizontally disposed tubular arbors 28, to each of which is fixedly attached a pulley 29. The two pulleys are staggered, the belts running over the same being actuated by a single pulley that is carried by a countershaft or other rotary means. The pulleys are provided with sleeve-like extensions 30, each of the pulleys abutting against one bearing of a set and the sleeve-like extension 30 attached thereto to the other bearing of the set, thereby preventing the tubular arbors 28 from moving in the direction of the longitudinal axes thereof in relation to the bearings. The bearings may be lubricated in any suitable manner (not shown in the drawings). Into each tubular arbor extends a stop 31, for instance a spindle, that is fastened in any suitable manner, for instance by a screw 32, to the main frame of the apparatus. To each arbor is secured, for instance by screw threads, a tubular knife or cutter 33, within which is loosely held an ejector 34, in the form of a rod, that is adapted to bear against its corresponding stop 31 as will appear hereinafter. The bearing block 26 is reciprocated by means of a cam 35, that is fixedly secured to the main driving shaft 23 and provided with a cam groove 36, into which extends a roller 37, that is carried by one end of a lever 38, the latter being pivoted at 39 to the main frame and being fork-

shaped at its other end, as clearly shown at 40, said fork-shaped end engaging with a roller 41, which is mounted upon the bearing block 26.

Upon two of the lining sleeves 22 is oscillatably mounted a frame 42, its sides 43 abutting against two of the bearings 21, whereby the said frame is prevented from moving in the direction of the longitudinal axis of the main driving shaft. This frame 42 extends up to a slight distance below the lower cutter of the machine, and is there provided with a forwardly extending projection 44, carrying upon each of its sides a latch 45, that is adapted to engage with a projection 45' on the main frame, said latch mechanisms being normally in engagement with the said projections to prevent a tilting of the frame 42. This frame is provided with two dove-tail grooves 46, which are disposed parallel to each other in a plane at 45° to the horizontal plane. Into these grooves reach the dove-tails 47 of a frame 48, which carries the work-holder and the feeding mechanism of the device. The frame 48 is provided with a downwardly projecting lug 49, in which is rotatably mounted a spindle 50, provided with screw threads 51, meshing with those of a screw threaded hole 52 in the frame 42. The spindle 50 is also disposed at an angle of 45°, and provided at its outer free end with a hand-wheel 53. By rotating the hand-wheel 53 the frame 48 will move up or down in the dove-tail grooves 46 of the frame 42, that is to say it will be raised or lowered, as the case may be, and simultaneously moved forward or backward in relation to the frame 42. The purpose of this arrangement will be described hereinafter.

The work holder of the device comprises two horizontally disposed plate members 54 and 55, which are attached in any suitable manner to the vertical side walls 56 of the frame 48, the plate 54 with parts hereinafter to be described forming the bottom of the work holder for the lower knife 33, and the plate 55 with the parts carried thereby and hereinafter to be described forming the bottom of the work holder coöperating with the upper knife 33. A third horizontal plate, denoted by the numeral 57, connects the top of the side walls 56 of the frame 48, the distance between the plates 54 and 55 being equal to the distance between the latter plate and the plate 57. In the upper faces of the plates 54 and 55 are provided grooves 58 and 59, and in each of these grooves is disposed a strip 60, which extends substantially throughout the length of its plate and projects a substantial distance in rear thereof beyond the cutters 33, as clearly appears from Fig. 2 of the drawings. These strips form the actual supports for the cork strips. The plate members 54, 55 and 57

are embraced by two box-like frames 61, one on each side of their longitudinal center lines, the latter coinciding with those of the strips 60. Each frame 61 consists of a top 5 plate 62, that is disposed upon the plate member 57, a bottom plate 63 abutting against the underface of the plate member 54, said top plate and bottom plate being connected by a vertically extending front post 64 and by a rear post 65. The front and rear posts are furthermore each connected by two vertical walls 66 and 67, the vertical walls 66 being disposed between the plate members 55 and 57, and the vertical walls 67 between the plate members 54 10 and 55. These two frames are held stationary on the plates 54, 55 and 57 at equal distances from the longitudinal center lines of these three plate members. The distances 15 may be adjusted according to the thicknesses of the cork strips to be worked upon. Between each vertical wall 66 and 67 and the adjacent side walls 56 of the frame 48 is disposed a slide 68, each slide being adapted 20 to be moved toward and away from the juxtaposed vertical walls 66 or 67 by means hereinafter to be described. Each slide 68 is provided with horizontal guideways 69, in which are seated the guide strips 70 of a 25 vertically disposed feed plate 71, each plate being normally located a substantial distance from the inner face of the corresponding vertical wall 66 or 67, and being provided with a plurality of horizontally disposed 30 feeding racks 72, which are adapted to project through longitudinal slots 73 in the vertical walls 66 and 67. The feed plates 71 are moved by means hereinafter to be described in parallel relation to the longitudinal 35 axes of the strips 60, and furthermore with the slides 68 toward and away from the said longitudinal center lines. Between the vertical portions 74 of each slide 68 and the corresponding feed plate 71 is disposed a 40 plurality of blade springs 75, to give the feeding racks some resiliency so as to prevent binding if a cork strip of somewhat thicker size happens to come upon the work-support. In each of the front posts 64 is 45 formed a vertically extending recess 76, and in each of the rear posts 65 a similar recess 77. In each of the recesses 76 is slidably disposed a bar 78, and in each of the recesses 77 a bar 79. In that face of each of 50 these bars which abuts against the corresponding slide 68 are provided two parallel curved substantially obliquely running grooves 80, in which are seated anti-friction 55 rollers 81, that are carried by lugs 82, the latter being attached to the slides 68. The 60 grooves 80 in those bars 78 and 79 which are disposed on the same side of the longitudinal center lines of the strips 60 run in the same directions, and so also the grooves 65 in the bars on the opposite side of the said

center lines, but the grooves in bars located at opposing sides of the said center lines run in opposite directions, whereby, as the four bars are simultaneously reciprocated, the slides 68 and the parts carried thereby 70 will move toward and away from said center lines. The bars are slidably pivoted to spindles 83, which are fixedly attached to a sliding head 84, the latter being reciprocably mounted upon the frame 48. The sliding 75 head is provided with a downwardly extending vertical extension 85, carrying a lug 86, on which is mounted an anti-friction roller 87, the latter extending into the cam groove 88 of a disk 90, that is fixedly attached to the main driving shaft 23. The extension 85 is made, for a purpose herein-after to be described, of two sections, denoted by the numerals 91 and 92, which overlap each other and are separated on a 80 line 93, that runs at 45° to the horizontal line in the same manner as the separating line between the frames 42 and 48. The sections 91 and 92 are united by a screw bolt 94, that is secured to the section 91 and 90 extends into a slot 95 in the section 92. The slot 95 runs at 45° to the horizontal line. A nut 96, bearing against the section 92, serves to hold the two parts of the extension 85 together. The cam groove 88 comprises 95 four distinct parts, each extending throughout an arc of 90°. From point I to point II of this groove the sliding head is kept stationary, from point II to point III it is raised, from point III to point IV it is 100 again kept stationary, and from point IV to point I it is lowered. When the sliding head is raised, the slides 68 move away from each other. They are kept stationary while the cam disk 90 makes a quarter of a turn, and are moved toward each other during a further quarter of a turn of the cam disk while the sliding head moves downward, and kept in their inner positions stationary 105 through a further quarter of a turn of said disk. 110

The feeding racks are actuated in the following manner: To each feeding plate 71 is fixedly attached an outwardly extending pin 97. These pins extend into two vertically disposed brackets 98, the base plates 99 of which are dove-tailed and slidably disposed in dove-tailed grooves 100 in the bottom plates 63 above mentioned. The base plates 99 carry downwardly extending fork-shaped lugs 101, in engagement with a spindle 102, which is keyed to a bellcrank lever 103. This bellcrank lever is fulcrumed at 104 in the frame section 48, its arm 105 carrying 115 an anti-friction roller 106, that is in contact with a slide 107. This slide moves in vertical guideways 108 in one of the sides of the frame section 48. A lug 109, in the form of a screw, is carried by the slide 107, and extends into a slot 110 in the sides of the frame 120 125 130

48, said lug and slot predetermining the lowermost position of the slide 107, and thus the stroke in one direction of the feeding racks. The slide 107 coacts with an eccentric 5 111, the said eccentric being, for instance, made integral with the cam wheel 90 above described. The eccentric 111 comprises, like the cam groove 88 above mentioned, four sections. From point I' to 10 point II' the slide 107 is lowered, from point II' to point III' it is stationary, the lug 109 resting then on the lower edge of the slot 110; from point III' to point IV' the slide is raised, and from point IV' to point I' it 15 is again kept stationary. From Fig. 10 of the drawings it appears that those points of the cam groove 88 and of the eccentric 111 which are located on the same radii are denoted by the same Roman numerals. 20 Bearing this in mind and comparing the motions of the sliding head 84 and the slide 107, it will appear that whenever the sliding head is in motion, the slide 107 is at rest, and vice versa. It also appears from 25 an inspection of the drawings that when the slides 68 move toward each other and thereby cause the feeding plates also to move in the same direction, the feeding racks do not move in the direction of the longitudinal 30 axis of the work-support; when, however, they have reached their innermost positions and the slides 68 are kept stationary, the feeding racks are moved toward the cutters a predetermined distance, that is to say 35 until the lug 109 rests upon the lower edge of the slot 110; and when the slides 68 recede from each other, the feeding racks do not move in the direction of the longitudinal axis of the work-support, and, finally, when 40 the slides 68 are kept stationary in their outermost positions, the feeding racks are moved away from the cutters a distance depending upon the throw of the slide 107. The brackets 98 are engaged by springs 112, 45 which are attached to the slides 68. These springs cause the racks to move toward the cutters, and at the same time keep the anti-friction roller 106 in contact with the slide 107. 50 In the rear posts 65 are formed horizontal guideways 113, in which are slidably disposed gripping jaws 114 in the form of box-like structures, one being associated with each of the posts 65. Each jaw 114 carries 55 two lugs 115, having anti-friction rollers 116, which are seated in grooves 117 in the bars 79. The grooves 117 in each bar run parallel to each other and are substantially obliquely arranged; they are, however, inclined in a direction opposite to that in which the grooves 80 above described run. For this reason, obviously, the jaws 114 move in directions opposite to those of the slides 68, that is to say whenever the slides 60 move toward each other, the jaws recede, 65

and when the slides recede, the jaws move toward each other. In those walls of the jaws which face each other, that is to say in those which are arranged in alinement with the walls 66 and 67 above mentioned, 70 there are detachably held two plate members 118, each being provided with two circular apertures 119 in vertical alinement with each other. The apertures of each set in one plate 118 register with those of the other and are in alinement with the tubular cutters 33. The apertures are of a somewhat larger diameter than the outer diameters of the cutters, and must, obviously, be replaced when the cutters are exchanged 75 for larger or smaller ones. In Fig. 18 one of these plates is shown, illustrating diagrammatically the manner in which the apertures in a set of plates are disposed. From this figure it will be observed that the 80 apertures all contact with a vertical line 120 and also with a horizontal line 121, their centers being disposed on a line 122, the latter running at 45° through the meeting point of the lines 120 and 121. The purpose of this arrangement will be explained 85 hereinafter. Around the apertures 119 are formed upon the inner faces of the plate members 118 ring-like milled projections 123, which contact, when the jaws are in 90 their innermost positions, with the cork strip, and keep the same in position during the cutting operation.

With each strip 60 is associated a presser foot 124. These presser feet are fixedly attached to rock-shafts 125 and 126, which are journaled in the sides 56 of the frame section 48. The presser feet are somewhat resilient, and their foot portions 127 are adapted to engage the tops of the cork strips 100 upon the work-support. To the rock-shafts 125 and 126 are fixedly attached levers 128 and 129, respectively, which are pivoted to links 130, the lower ends of which are pivoted at 131 to levers 132, the latter being 105 fulcrumed at 133 to the sliding head 84. The pivots 131 move in registering arc-shaped slots 134 in the sliding head 84 and in the side plates 56 of the frame section 48. To the frame section 42 are fulcrumed 111 at 135 levers 136, that carry at their free ends a spindle 137, that is seated in slots 138 in the levers 132. The said spindle is also seated in slots 139 in the side walls 56 of the frame section 48. Whenever the sliding head 84 moves upward, the presser feet are caused to move into contact with the cork strips by means of the connections above described; that is to say when the sliding head moves upward, the levers 132 115 swing around the spindle 137, their pivot spindles 131 moving in the arc-shaped slots 134 downward, and causing thus the presser feet to move into contact with the cork strips. The presser feet are somewhat resil- 120 125 130 135 140

ient to adapt them to the irregularities of the upper faces of the cork strips. Inasmuch as the presser feet are actuated by the sliding head in the manner above indicated, 5 it will be obvious that whenever the jaws 114 move into contact with the cork strips, the presser feet are depressed, and when the said jaws recede from each other, the presser feet are lifted. However, the presser feet 10 engage the cork strip previous to it being gripped by the jaws 114, that is to say they are forced onto the supporting strips 60 before they are gripped by the jaws above mentioned.

15 To the projection 44 of the frame section 42 are attached below the cutters 33 an inclined plate 140, and in rear of the strips 60 an inclined plate 141. The inclined plate 140 directs the corks into a receptacle placed 20 in rear of the machine, and the inclined plate 141 the waste into another container.

The operation of this device is as follows: In the positions of the parts shown in the several figures of the drawings the 25 sliding head 84 is shown in its uppermost position. When in this position the gripping jaws 114 are in engagement with the sides of the cork strip, and the presser feet held against the upper face of the latter. 30 The slides 68 and thus the feeding racks are in their outermost positions in relation to the longitudinal axis of the work-support. The cork strips are placed upon the supports, that is to say upon the strips 60, and 35 advanced manually until they are within the reach of the feeding racks. When the sliding head is in its upper position, it stops there during a quarter of a turn of the main driving shaft 23, and during this time the 40 cam 35 moves the bearing block 26 toward the work-support, whereby the cutters block out corks from the strips on the support. From this it will be observed that during 45 the cutting operation, the gripping jaws and the presser foot hold the cork strips against motion. While the cutting operation takes place, more particularly during the time the gripping jaws and the presser foot hold the cork strip against movement, the slide 107 is 50 raised, whereby the feeding racks move away from the cutters. During the next quarter of a turn of the main driving shaft, the sliding head 84 is lowered, thereby bringing the feeding racks into engagement 55 with the cork strips. During the same time the gripping jaws recede and the presser foot is lifted, and the cutters are withdrawn from the cork. The rods 34, in abutting against the stops 31, eject the corks from 60 the cutters. During the next quarter of a turn of the main driving shaft, the sliding head 84 is kept in its lower position stationary, and the slide 107 is lowered, whereby 65 the springs 112 are adapted to act on the feeding racks, which will move the cork

strips a predetermined distance toward the cutters. The sliding head moves then upward, causing the gripping jaws and the presser foot to engage the cork, and at the same time the slides 68 to move away from the cork strips. The cycle of operation now described is then repeated.

In the drawings the parts of the machine are shown in the positions which they occupy when cutting corks of the smallest 75 diameter. If corks of a larger diameter are to be cut, first of all the cutters 33 are moved into their outermost positions, in which they clear the gripping jaws. The latches 45 are then disengaged from the keepers, and 80 the frame 48 with the parts carried thereby swung around the main driving shaft 23 in the position shown in dotted lines in Fig. 21, after which the cutters are removed from the arbors 28, and replaced by those of the 85 desired larger diameter. The plate members 118 are then taken off the gripping jaws, and replaced by those having openings corresponding to the diameters of the knives. The frame sections 48 and 42 are then 90 swung back into their normal positions, in which the latches 45 are engaged with their keepers. The nut 96 is then loosened, and the hand-wheel 53 turned until the tubular cutters are properly in alignment with the 95 apertures 119 in the plate members 118. After this the nut 96 is tightened, to properly connect the two sections of the extension 85 of the sliding head. Due to the fact that the frame section 48 slides on the frame 100 section 42 under an angle of 45°, by the above described operation the frame section 48 will be lowered in relation to the frame section 42, and simultaneously moved away from the cutters the same distance (see position shown in dotted lines in Fig. 22). The adjustment is in all cases such that the lines 120 and 121, shown in the diagram in Fig. 18 of the drawings, always contact with the edges of the cutters. It is to be observed 105 that the feeding racks in their movement toward the cutters stop always at the very same point, and it is only the throw in the opposite direction which is varied by the setting above described. For this reason 110 naturally the cork strips are moved a predetermined distance toward the cutters, and distances between the cuts are always the same, no matter whether corks of larger or smaller diameters are being blocked, and 115 the cork strips are fed up to their very ends to the cutters, so that the wasting of material is effectively prevented.

It is to be observed that, as the frame section 48 and the parts carried thereby are 120 lowered and removed from the centers of the cutters for the purpose above described, the distance between the spindles 133 and 137 will be enlarged for the reason that the spindle 137 is carried by the levers 136, 130

which are fulcrumed to or stationary part of the frame. For this reason the arc through which the pivots 131 are swung is decreased and so also the swing of the 5 presser foot. This is necessary for the reason that corks of larger diameters are cut from wider strips.

Attention is called to the fact that the 10 slide 107 in its lowermost position does not contact with the eccentric 111. When the frame section 48 and the parts carried thereby are lowered, as above described, the slide 107 is brought nearer to the eccentric 111. As now this eccentric turns, the upward 15 throw of the slide 107 will be naturally greater, and thereby also the backward movement of the feeding racks. The slide 107 is continuously in contact with the eccentric 111 when corks of the largest diam- 20 eters are to be cut on the machine.

From the foregoing it appears that by 25 turning the hand-wheel 53 in the proper direction, all parts are set according to the diameters of the corks to be cut. With the hand-wheel 53 can, obviously, be associated a graduated scale. This element has not been shown as the same does not form an essential part of the invention.

The frames 61 must be adjusted in relation to the longitudinal axis of the support 30 according to the thickness of the cork strips. These frames may be clamped in any suitable manner, for instance by means of screws, to the plates 54, 55 and 57, after 35 bringing them to the desired positions. The bars 78 and 79 slide on the pivot spindles 83 and the lugs 101 on the spindle 102 of the bellcrank 103.

What I claim is:—

- 40 1. In a cork blocking machine, the combination with a main frame, of a rotary cutter arranged thereon, and a work-support carrying frame on said main frame shiftable in a plane intersecting at 45° a horizontal plane placed through said cutter, a support on said second frame for the cork strip to be worked upon, a plurality of feeding racks 45 slidably disposed on both sides of the longitudinal axis of said support and in parallel relation to said axis, means for reciprocating said racks, means for actuating said gripping jaws and for causing said racks to move toward each other and thus 50 to grip the cork strip, said racks being kept in gripping positions while the same complete their forward stroke, whereby the cork strip is advanced a predetermined distance, and for causing said racks to move away 55 from each other at the end of their advanc-
- 50 2. In a feeding device for cork blocking machines, the combination with a support for the cork strip to be worked upon, of gripping jaws, a plurality of feeding racks 55 slidably disposed upon both sides of the longitudinal axis of said support and in parallel relation to said axis, means for reciprocating said racks, means for actuating said gripping jaws and for causing said racks to move toward each other and thus 60 to grip the cork strip, said racks being kept in gripping positions while the same complete their forward stroke, whereby the cork strip is advanced a predetermined distance, and for causing said racks to move away 65 from each other at the end of their advanc-

ing stroke, thereby releasing the cork strip, said gripping jaws being actuated to engage the cork strip after each advancing stroke of said racks.

3. In a feeding device for cork blocking 70 machines, the combination with a support for the cork strip to be worked upon, of gripping jaws, a plurality of feeding racks 75 slidably disposed upon both sides of the longitudinal axis of said support and in parallel relation to said axis, means for reciprocating said racks, means for actuating said gripping jaws and for causing said racks to move toward each other and thus 80 to grip the cork strip, said racks being kept in gripping positions while the same complete their forward stroke, whereby the cork strip is advanced a predetermined distance, and for causing said racks to move away 85 from each other at the end of their advancing stroke, thereby releasing the cork strip, said gripping jaws being actuated to engage the cork strip after each advancing stroke of said racks, and a presser-foot acting upon the top of the cork strip simultaneously 90 with said gripping jaws.

4. In a cork blocking machine, the combination with a main frame, of a rotary cutter arranged thereon, a work support carrying frame on said main frame shiftable in 95 a plane intersecting at 45° a horizontal plane placed through said cutter, a support on said second frame for the cork strip to be worked upon, a plurality of feeding racks 100 slidably disposed on both sides of the longitudinal axis of said support and in parallel relation to said axis, a rotary shaft on said main frame, a sliding head upon said second frame, means upon said shaft for actuating said sliding head, means upon said sliding 105 head for causing said racks to move toward each other and thus to grip the cork strip, springs for advancing said racks while being kept in gripping positions, whereby the cork strip is fed a predetermined distance 110 toward said cutter, said first named means upon said sliding head causing said racks to move away from each other at the end of their advancing stroke, thereby releasing the cork strip, means upon said second 115 frame for moving said racks in a direction opposite to that effected by said springs, and means upon said shaft for actuating said last named means.

5. In a cork blocking machine, the combination with a main frame, of a rotary cutter arranged thereon, a work-support carrying frame on said main frame shiftable in a plane intersecting at 45° a horizontal plane placed through said cutter, a support on 125 said second frame for the cork strip to be worked upon, a plurality of feeding racks 130 slidably disposed on both sides of the longitudinal axis of said support and in parallel relation to said axis, a rotary shaft on 130

5 said main frame, a sliding head upon said second frame, means upon said shaft for actuating said sliding head, means upon said sliding head for causing said racks to move toward each other and thus to grip 10 the cork strip, springs for advancing said racks while being kept in gripping positions, whereby the cork strip is fed a predetermined distance toward said cutter, the first named 15 means upon said sliding head causing said racks to move away from each other at the end of their advancing stroke, thereby releasing the cork strip, means upon said second frame for moving said racks in a direction opposite to that effected by said 20 springs, means upon said shaft for actuating said last named means, and gripping jaws engaging the cork strip after each advancing stroke of said racks, said gripping jaws being actuated by said sliding head.

6. In a cork blocking machine, the combination with a main frame, of a rotary cutter arranged thereon, a work-support carrying frame on said main frame shiftable in 25 a plane intersecting at 45° a horizontal plane placed through said cutter, a support on said second frame for the cork strip to be worked upon, a plurality of feeding racks slidably disposed on both sides of the 30 longitudinal axis of said support and in parallel relation to said axis, a rotary shaft on said main frame, a sliding head upon said second frame, means upon said shaft for actuating said sliding head, means upon said 35 sliding head for causing said racks to move toward each other and thus to grip the cork strip, springs for advancing said racks while being kept in gripping positions, whereby the cork strip is fed a predetermined 40 distance toward said cutter, said first named means upon said sliding head causing said racks to move away from each other at the end of their advancing stroke, thereby releasing the cork strip, means upon said second frame for moving said racks in a direction opposite to that effected by said 45 springs, means upon said shaft for actuating said last named means, gripping jaws engaging the cork strip after each advancing 50 stroke of said racks, said gripping jaws being actuated by said sliding head, and a presser foot adapted to act upon the top of the cork strip, said presser foot being actuated by said sliding head simultaneously 55 with said gripping jaws.

7. In a cork blocking machine, the combination with a main frame, of a rotary cutter arranged thereon, a work-support for the cork strip, a plurality of feeding racks slidably disposed on both sides of the longitudinal 60 axis of said support and in parallel relation to said axis, a rotary shaft on said main frame, a sliding head, means upon said shaft for actuating said sliding head, means upon 65 said sliding head for causing said racks to

move toward each other and thus to grip the cork strip, springs for advancing said racks while being kept in gripping positions, whereby the cork strip is fed a predetermined distance toward said cutter, the first named 70 means upon said sliding head causing said racks to move away from each other at the end of their advancing stroke, thereby releasing the cork strip, means for moving said racks in the direction opposite to that effected 75 by said springs, and means upon said shaft for actuating said last named means.

8. In a cork blocking machine, the combination with a main frame, of a rotary cutter arranged thereon, a work-support for the 80 cork strip, a plurality of feeding racks slidably disposed on both sides of the longitudinal axis of said support and in parallel relation to said axis, a rotary shaft on said main frame, a sliding head, means upon said shaft for actuating said sliding head, means upon said sliding head for causing said racks to move toward each other and thus to grip the cork strip, springs for advancing said racks while being kept in gripping positions, whereby 90 the cork strip is fed a predetermined distance toward said cutter, the first named means upon said sliding head causing said racks to move away from each other at the end of their advancing stroke, thereby releasing the 95 cork strip, means for moving said racks in the direction opposite to that effected by said springs, means upon said shaft for actuating said last named means, and gripping jaws engaging the cork strip after each advancing 100 stroke of said racks, said gripping jaws being actuated by said sliding head.

9. In a cork blocking machine, the combination with a main frame, of a rotary cutter arranged thereon, a work-support for the 105 cork strip, a plurality of feeding racks slidably disposed on both sides of the longitudinal axis of said support and in parallel relation to said axis, a rotary shaft on said main frame, a sliding head, means upon said shaft for actuating said sliding head, means upon said sliding head for causing said racks to move toward each other and thus to grip the cork strip, springs for advancing said racks while being kept in gripping positions, 110 whereby the cork strip is fed a predetermined distance toward said cutter, the first named means upon said sliding head causing said racks to move away from each other at the end of their advancing stroke, thereby releasing the 115 cork strip, means for moving said racks in the direction opposite to that effected by said springs, means upon said shaft for actuating said last named means, and a presser foot adapted to act upon the top of the cork strip, said presser foot being actuated by said sliding head.

10. In a cork blocking machine, the combination with a main frame, of a rotary cutter arranged thereon, a work-support, feeding 130

means on said work-support for advancing the cork strip to said cutter, a presser foot adapted to act upon the top of the cork strip, and means for simultaneously adjusting the position of said work-support in relation to said cutter, the extent of the feed of said feeding means and the stroke of said presser foot.

11. In a cork blocking machine, the combination with a main frame, of a rotary cutter arranged thereon, a work-support, a plurality of feeding racks slidably disposed upon both sides of the longitudinal axis of said support and in parallel relation to said axis, means for causing said racks to move toward each other and thus to grip the cork strip, springs for advancing said racks while being kept in gripping positions, whereby the cork strip is fed a predetermined distance toward 20 said cutter, said first named means causing said racks to move away from each other at the end of their advancing stroke, thereby releasing the cork strip, means for moving said racks in the direction opposite to that

effected by said springs, and means for simultaneously adjusting the position of said work-support in relation to said cutter and the movement of said racks in the direction opposite to that effected by said springs. 25

12. In a cork blocking machine, the combination with a main frame, of a rotary arbor thereon, a cutter on said arbor, a work support, feeding racks slidably disposed on said work-support, means on said work-support for advancing said racks to feed the cork strip 30 toward said cutter, and means for adjusting the position of said work-support in relation to said cutter and thereby correspondingly varying the extent of the feed of said racks in relation to the longitudinal 35 axis of said arbor. 40

Signed at New York, in the county of New York and State of New York, this 20th day of Feb., A. D. 1915.

ALEXANDER BOGDÁNFFY.
